UNITED STATES PATENT OFFICE.

FREDRIK LJUNGSTRÖM, OF BREVIK, LIDINGON, SWEDEN.

MEANS FOR PREVENTING FORMATION OF RUST IN TURBINES BEING AT REST.

Application filed March 23, 1921. Serial No. 454,950.

To all whom it may concern:

Be it known that I, FREDRIK LJUNGSTRÖM, chief engineer, a subject of the King of Sweden, residing at Brevik, Lidingon, Sweden, have invented certain new and useful Improvements in Means for Preventing Formation of Rust in Turbines Being at Rest, of which the following is a specification.

10 Steam and gas turbines are, as well known, connected with the inconvenience that their inner members, especially when being at rest, are liable to become rusty, and on account thereof several methods have been proposed 15 with the object of preventing said drawback. Thus for instance efforts have been made to procure a material for the blades and other inner members not liable to become rusty. Since, however, it has proved difficult to 20 produce such a material of sufficient strength and not liable to rust for the manufacture of the blades, the same difficulty remains constantly. The formation of rust arises from the inner members of the turbine, when 25 at rest, being surrounded by air or gas which, just after the stopping of the turbine, is hot and saturated with moisture adapted to deposit in the form of water on the inner members of the turbine while being 30 cooled.

This invention relates to means for preventing the formation of rust on the inner members of the turbine by the air or gas within the turbine being heated or kept at 35 such a temperature that it becomes relatively dry.

The invention consists in that a heating element is placed inside the turbine or its outlet, the element, upon each stand-still of 40 the turbine, heating the air or gas circulating around the inner members of the same. Preferably said heating element consists of a steam spiral tube connected with a boiler, for instance the steam boiler plant pertinent to the turbine aggregate, the steam flowing 45 through said tube at least upon each stand-still of the turbine.

The invention is illustrated in two embodiments on the accompanying drawing, in 50 Fig. 1 applied to an action turbine and in Fig. 2 to a turbine substantially of reaction type.

Referring to Fig. 1, 1 designates the turbine disk provided with the moving blades 55 2. The steam flowing from the steam inlet 3 through the nozzle 4 actuates the turbine

wheel and escapes through the outlet 5. The steam surrounding the inner members of the turbine is prevented from being cooled and consequently moisture is also prevented from 60 being deposited on said inner members by means of the heating element 8 placed in the outlet 5 and heating the said steam.

It is the same case in the turbine shown 65 in Fig. 2 into which the steam entering through nozzles actuates the turbine wheel or drum 1 and then, while transmitting its effect, passes the blade system 12 to the outlet 5 where the heating element 8 is placed.

The heating element may be placed at any 70 point within the turbine or its steam conduits. In certain turbine types the element is preferably mounted in the steam conduit between the turbine and the condenser or 75 altogether or in part in the condenser.

The steam may flow through the element either continually or only when the turbine is at rest.

In the latter case the construction may be 80 executed according to Fig. 2 in which 21 designates the steam inlet, 23 the inlet to the element and 24 the inlet to the turbine, 22 designating a valve device which connects 21 either with 23 or with 24. Obviously many other connections may be conceived so arranged that the connection between the boiler and the element is shut off, when steam is admitted to the turbine, but open when said admission is shut off.

What I claim as new and desire to secure 90 by Letters Patent of the United States is:

1. In combination a turbine and its casing, and a heating element placed within the 95 casing and arranged to heat the gaseous medium in the turbine, so as to prevent the formation of rust.

2. In combination a turbine and its casing, and a conduit for the gaseous medium, a 100 heating element being placed within said conduit and arranged to heat the gaseous medium, so as to prevent the formation of rust.

3. In combination a turbine and its casing, and an outlet conduit for the gaseous medium, a heating element being placed within said outlet conduit and arranged to heat the gaseous medium, so as to prevent 105 the formation of rust.

4. In combination a turbine and its casing, and a heating element placed within the 110 casing, said heating element being supplied

with steam and arranged to heat the gaseous medium in the turbine, so as to prevent the formation of rust.

5. In combination a steam turbine and its casing, a heating element placed within the casing, and a steam supply to said heating element and to the turbine and arranged to supply steam to either, so as to heat, when supplied to the heating element, the gaseous medium in the turbine, whereby the formation of rust is prevented. 30

6. In combination a steam turbine and its casing, and a steam outlet from the turbine, a heating element being placed within said outlet, and a steam supply to said heating element and to the turbine and arranged to supply steam to either, so as to heat, when applied to the heating element, the gaseous medium in the turbine, whereby the formation of rust is prevented. 35

7. In combination a steam turbine and its casing, a heating element placed within said casing, and a steam conduit connected with the turbine and with the heating element, and means inserted in said steam con- 40

duit and arranged to supply steam either to the turbine or to the heating element, so as to heat, when supplied to the heating element, the gaseous medium in the turbine, whereby the formation of rust is prevented. 30

8. In combination a steam turbine and its casing, a steam passage within said casing, and a heating element placed in said steam passage and arranged to heat the gaseous medium in the turbine, so as to prevent the formation of rust. 35

9. In combination a steam turbine and its casing, a steam passage within said casing, and a heating element placed in said steam passage and supplied with steam independent of said passage and arranged to heat the gaseous medium in the turbine, so as to prevent the formation of rust. 40

In testimony whereof I affix my signature in presence of two witnesses.

FREDRIK LJUNGSTRÖM.
